X-RAY CONTRAST AGENT

Hans Priewe, Berlin-Steglitz, Alexander Poljak, Berlin-Frohnau, and Karl Junkmann, Berlin, Germany, assignors to Firma Schering A.G., Berlin, Germany
No Drawing. Filed Dec. 9, 1958, Ser. No. 779,065
Claims priority, application Germany Dec. 18, 1957
12 Claims. (Cl. 167—95)

The present invention relates to X-ray contrast agents, and more particularly to X-ray contrast agents suitable for peroral administration to serve as a contrast agent for the taking of X-ray pictures of the gall bladder and in general for cholecystography.

It is a primary object of the present invention to provide new X-ray contrast agents for peroral administration which are suitable for cholecystography.

It is another object of the present invention to provide for the production of the new compounds of the present invention.

Other objects and advantages of the present invention will be apparent from a further reading of the specification and of the appended claims.

With the above objects in view, the present invention mainly comprises a compound selected from the group consisting of compounds of the following general formula:

wherein R is a hydrocarbon radical of 1-6 carbon atoms, and non-toxic salts thereof.

It has been discovered that while α -alkyl- β -(3-amino-2,4,6-triiodophenyl)-propionic acids are suitable as X-ray contrast agents for the taking of X-ray pictures of the gall bladder, the diamino compounds of the present invention have many advantages over the above mentioned monoamino compounds.

Among the advantages of the compounds of the present invention are: considerably lower toxicity, a markedly excellent resorbability upon peroral administration, and a preferred deposition in the gall with a simultaneous increased degree of contrast development. Furthermore, the new compounds of the present invention have the advantage of being able to leave the body, if necessary, through the urinary tract, which in the case of occlusions of the bile duct represents a considerable advantage as compared to the above mentioned monoamino compounds which do not have this property.

The compounds of the present invention are primarily useful as radiopaque substances to be given orally for cholecystography, these compounds being given in the form of the free acids or in the form of their non-toxic salts. The compounds may also, however, be given for the purpose of taking X-ray pictures of other organs than the gall bladder, such as body cavities in general.

As indicated above, the substituent "R" is a hydrocarbon radical of preferably 1-6 carbon atoms. Preferably, the substituent "R" is an alkyl or cycloalkyl radical of 1-6 carbon atoms.

The compounds may be used in the form of the free acids or in the form of non-toxic salts thereof with inorganic or organic bases. Among the suitable salts which may be mentioned are: the methylglucamine, ammonium, sodium, lithium, potassium, calcium, glucamine, ethylglucamine, ethanolamine, diethanolamine and triethanolamine salts.

The compounds may be mixed with suitable pharmaceutical excipients and made up into a form suitable for

2

oral administration, for example in the form of capsules, dragees, and the like.

The compounds of the present invention are preferably produced by iodinating a compound having the following general formula:

wherein R has the same definition as above. The iodination is most conveniently carried out according to generally known iodination methods, for example by means of chloroiodide in hydrochloric acid solution, or by means of potassium iodide-dichloride in neutral or weak hydrochloric acid solution. The resulting triiodinated compound may be used as such, or it may be reacted with a non-toxic inorganic or organic base to form the corresponding non-toxic salt thereof.

20 The starting substance from which the compounds of the present invention are formed, i.e.:

25 may be produced according to the methods generally used in organic synthesis for the production of similar compounds, for example from 3,5-dinitrobenzoyl-acetic ester by introducing into the α -position in known manner the desired aliphatic or cycloaliphatic radical. This is carried out, for example, by reacting the sodium enolate of the 3,5-dinitrobenzoyl-acetic ester in alcoholic solution with an alkyl or cycloalkyl halogenide, e.g. chloromethyl, isopropylbromide, hexyl iodide, or the like. Upon hydrogenation the corresponding β -3,5-diaminophenyl- β -hydroxy- α -alkyl- or cycloalkyl-propionic acid ester is obtained. By reaction with thionyl chloride, the β -position hydroxyl is replaced by chlorine, which is subsequently replaced by hydrogen by means of hydrogenation.

30 The following examples are given to further illustrate the present invention. The scope of the invention is not, however, meant to be limited to the specific details 45 of the examples.

Example 1

18 g. of α -ethyl- β -(3,5-diaminophenyl)-propionic acid-ethyl ester are heated for saponification with a mixture of 150 cc. of 3 N sodium hydroxide and 250 cc. of methanol for 3 hours to boiling under reflux conditions. The reaction mixture is then acidified with dilute hydrochloric acid and the methanol is driven off under vacuum.

50 The distillation residue is diluted with ice water to 1200 cc. and 90 cc. of 2 N potassium iodide-dichloride solution is added dropwise under stirring. The precipitated sand colored precipitate is subjected to suction filtration, washed with water and dissolved in ether.

55 The solution which is dried over sodium sulfate is reacted with alcoholic sodium hydroxide which results in precipitation of the sodium salt of α -ethyl- β -(3,5-diamino-2,4,6-triiodophenyl)-propionic acid. The salt is filtered by suction, dissolved in water, and the free acid is precipitated from the aqueous solution by means of dilute hydrochloric acid. The yield of the air-dried product is 65 24 g. The melting point is above 85° C., with decomposition.

70 By treatment with benzene under cold conditions and subsequent recrystallization from a large amount of benzene, the substance is obtained in the form of practically colorless crystals having a melting point of 156.5-157° C., with decomposition. The salt may be obtained

by neutralization of the acid in aqueous solution with the corresponding base, and then freezing-drying.

Example 2

10 kg. of the α -ethyl- β -(3,5-diamino-2,4,6-triiodophenyl)-propionic acid produced according to Example 1 are kneaded in a kneading machine with 4 liters of starch paste containing 200 g. of corn starch. The wet mass is granulated in a normal manner in a granulation machine and then dried under vacuum. The finished granulate is then mixed with 1 kg. of corn starch and 50 g. of magnesium stearate and pressed into tablets each containing 500 mg. of the active ingredient.

Example 3

The easily water soluble sodium salt of α -ethyl- β -(3,5-diamino-2,4,6-triiodophenyl)-propionic acid produced according to Example 1 is introduced into gelatin capsules filling the same. Each capsule contains 750 mg. of the active substance. For machine production of capsules the sodium salt can be mixed with a 40% mixture of corn oil, soybean lecithin and cocoa fat to a flowing paste.

Example 4

The granulate produced according to Example 2 is with 20% of the weight thereof of sugar syrup formed into dragees in a dragee vessel, and subsequently waxed.

Without further analysis, the foregoing will so fully reveal the gist of the present invention that others can by applying current knowledge readily adapt it for various applications without omitting features that, from the standpoint of prior art, fairly constitute essential characteristics of the generic or specific aspects of this invention and, therefore, such adaptations should and are intended to be comprehended within the meaning and range of equivalence of the following claims.

What is claimed as new and desired to be secured by Letters Patent is:

1. A compound selected from the group consisting of compounds of the following general formula:

wherein R is a hydrocarbon radical of 1-6 carbon atoms; and non-toxic salts thereof.

2. A compound having the following general formula:

wherein R is an alkyl radical of 1-6 carbon atoms.

3. A compound having the following general formula:

wherein R is a cycloalkyl radical of 1-6 carbon atoms.

4. A non-toxic salt of a compound having the following general formula:

wherein R is an alkyl radical of 1-6 carbon atoms.

5. A non-toxic salt of a compound having the following general formula:

wherein R is a cycloalkyl radical of 1-6 carbon atoms.

6. The sodium salt of a compound having the following general formula:

wherein R is an alkyl radical of 1-6 carbon atoms.

7. The sodium salt of a compound having the following general formula:

wherein R is a cycloalkyl radical of 1-6 carbon atoms.

8. The methylglucamine salt of a compound having the following general formula:

wherein R is an alkyl radical of 1-6 carbon atoms.

9. The methylglucamine salt of a compound having the following general formula:

wherein R is a cycloalkyl radical of 1-6 carbon atoms.

10. α -Ethyl- β -(3,5-diamino-2,4,6-triiodophenyl)-propionic acid.

11. The sodium salt of α -ethyl- β -(3,5-diamino-2,4,6-triiodophenyl)-propionic acid.

12. An X-ray contrast composition for peroral administration, comprising a compound selected from the group consisting of compounds of the following general formula:

wherein R is a hydrocarbon radical of 1-6 carbon atoms, and non-toxic salts thereof; and pharmaceutical excipients adapted for peroral administration.
